Inventor:

Burnham Stickney

UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

STENCILING-MACHINE.

1,370,240.

Specification of Letters Patent.

Patented Mar. 1, 1921.

Application filed July 9, 1919. Serial No. 309,700.

To all whom it may concern:

Be it known that I, BURNHAM C. STICKNEY, a citizen of the United States, residing in Elizabeth, in the county of Union and State of New Jersey, have invented certain new and useful Improvements in Stenciling-Machines, of which the following is a specification.

This invention relates to stenciling devices, and is herein disclosed as applied to a revolving duplicator in which a stencil sheet is stretched around the periphery of a revoluble cylinder. An inked mat or surface upon the cylinder forces ink through 15 the stenciled sheet upon the work-sheet.

In such devices it is important that any 20 adjustments be simple and dependable, inasmuch as the devices are usually put into the hands of persons unfamiliar with the use of machinery.

One of the difficulties in obtaining satisfactory impressions from a stenciling device of the class described, arises from the fact that the work-sheet or impression paper 25 is held against the stencil surface by a roller, which must press smoothly, evenly and with the proper tension to insure a good impression.

The present invention is especially directed to devices for insuring an even pressure of the roller, and to the provision of means whereby an inexperienced person may readily adjust such pressure.

To this end the impression roller is held 30 up against the cylinder, or the work thereon, by means of two main springs, one at each end of the roller; these springs being preferably adjustable, and preferably arranged to be adjusted permanently when manufacturing, their adjustment not to be disturbed by the user of the machine. These springs 35 act upon levers, through which they operate upon the roller. The levers are connected by a cross-rod, to the middle portion of 40 which is connected a third spring, which 45 constantly tends to release the roller from the stencil cylinder. The tension of this releasing spring is regulatable by the operator, by turning a single nut, permitting 50 him to adjust the strength of the opposition that is exerted by the releasing spring against the tension that is exerted by the main springs, until just the right pressure of the roll against the impression cylinder is 55 secured. Moreover, the point at which this releasing or counter-acting spring acts upon

the cross-rod may be shiftable, so that it will exert greater pressure upon either lever than upon the other, as may be required in evening up the ends of the roller, or adapting it for different kinds of work. Whenever it is desired to release the roller from the cylinder, said releasing spring is given an extra tension by turning a handle, thereby overcoming the tension of the main 60 springs, and drawing down the roller. Upon reversing the handle, the roller is restored by the main springs.

Other features and advantages will hereinafter appear.

In the accompanying drawings,

Figure 1 is an end view, largely diagrammatic, showing the impression cylinder and the frame, parts being broken away.

Fig. 2 is a detail view of the devices for 75 adjusting the spring pressure of the roller.

Fig. 3 is a detail side view, showing the adjusting devices manipulated by a finger-piece to withdraw the roller from the cylinder.

Fig. 4 is a fragmentary perspective view 80 of the roller and the principal parts connected therewith.

Fig. 5 is a perspective view of a device for positioning the adjusting spring toward 85 one side or the other.

The cylinder 10 of the duplicating devices is mounted to revolve about a horizontal axis in a frame 11 having rolls 12, and is adapted to carry on its foraminous surface 90 13 a stencil sheet, against which an impression sheet or work-sheet is adapted to be pressed by a roller 14. The impression sheets are fed to the bite of the roller 14 upon the cylinder 10 over a paper table 95 (not shown), and are delivered to another paper table (not shown).

According to the present invention, the roller 14, which may be of any suitable material, is provided with gudgeons 15 which 100 revolve in journals 16, formed as depressions in swinging bars or levers 17. The bars 17 are pivoted upon pins 18, and are pressed up by springs 19, which bear against set screws 20, threaded into brackets 21, projecting inwardly from the standards 22 of the frame. The springs 19 are held against slipping on the bars 17 because they fit around pins 23 upon said bars. The machine is usually sent out from the factory 110 with the screws 20 properly adjusted to evenly raise the two bars 17, so that, when

used, the roller 14 will produce an even pressure of the impression paper upon the cylinder 10. The two bars 17 are herein shown as flat strips having ends 24 turned over vertically to have joined loosely to them the ends 25 of a cross-bar 26.

To enable the operative to vary the pressure of the roller 14 upon the cylinder 10, if ever required by the character of the ink 10 or the kind of impression paper, or for any other reason, there is provided a tension spring 27, which is adapted to draw down the cross-bar or piece 26 and with it the roller 14 against the tension of the compression springs 19. To enable the tension of the spring 27 to be adjusted, it is connected at its lower end to an eye bolt 28, which passes through a lug 29 of an arm 30 and carries a thumb-screw-nut 31 threaded 20 onto the bolt beneath the lug 29, with the result that the spring 27 may be tensioned by screwing up the thumb-nut 31. The spring 27 may be of considerable length so that a considerable variability of adjustment 25 may be made, it being strong enough to overcome both of the springs 19, if tensioned strongly enough, as will hereinafter appear.

If the operative finds that there is unevenness of stenciling, or that, for any reason, either side of the roller 14 holds the impression paper too tightly upon the cylinder 10, the spring 27 may be caused to pull down more upon that end of the cross-piece 26. To enable this to be done, the spring 27, instead of drawing directly upon the cross-piece 26, draws upon nut 33 threaded upon the cross-piece 26. At its middle, the upper end 34 of the spring 27 40 is bent to an angle to fit the squared portion 32, thus preventing the thumb-screw or nut 33 from turning accidentally. There are collar portions 35 upon the sides of the squared portion 32. The spring 27 lifts or 45 yields as the thumbscrew 33 is turned, since the spring hook catches loosely over the part 32. The end 34 of the spring is carried nearer one or the other end of the cross-piece 26, depending upon which way the nut 50 33 is turned. If, for example, the operative finds that the roller 14 bears too heavily upon the right-hand end of the cylinder 10, the nut 33 is screwed toward said right-hand end until the shifting of the tension of the 55 spring 27 properly adjusts the relative tension of the two ends of the roller 14.

To enable the roller 14 to be entirely withdrawn from the cylinder 10, the arm 30 is formed as a rock-arm upon a shaft 36, journaled in the standards of the frame 11, and shaft 36 is provided with a second rock arm 37, connected by a link 38 to a pivoted finger-piece 39. In the Fig. 3 position, the link 38 is carried past the dead center, with 60 the result that the tension of the spring 27

upon it draws the finger-piece around until it is arrested by a stop 40, which therefore holds the roller 14 in its lowered position. In order to prevent the spring 27 from pulling the arm 30 too far upward, 70 there may be provided a stop 41, against which the end 42 of the rock arm 37 may strike. This stop is herein shown as a set screw threaded into a lug 43, thus enabling it to be adjusted, as desired. Such provision for adjustment, however, will in many cases be unnecessary, since all necessary adjustment can be effected by turning the thumb-screw 31. For convenience in construction, the lug 29 may be in the form of 80 a shouldered bolt passing through the rock arm 30 with a nut 44 threaded onto it.

Variations may be resorted to within the scope of the invention, and portions of the improvements may be used without others. 85

Having thus described my invention, I claim:

1. In a duplicating device, the combination with a cylinder and a pressure roll, of a swinging journal for each end of the roll, 90 a spring for each journal adapted to support it to hold the pressure roll against the cylinder, a cross-piece connecting said journals, and a resilient device adapted to variably draw down on said cross-piece to 95 vary the pressure of the roll upon the cylinder.

2. In a duplicating device, the combination with a cylinder and a pressure roll, of a swinging journal for each end of the roll, 100 a spring for each journal adapted to support it to hold the pressure roll against the cylinder, a cross-piece connecting said journals, a resilient device adapted to variably draw down on said cross-piece to vary 105 the pressure of the roll upon the cylinder, and means to shift the device along the cross-piece to alter the relative pressure of the two ends of the roll upon the cylinder.

3. In a duplicating device, the combination with a cylinder and a pressure roll, of a swinging journal for each end of the roll, 110 a spring for each journal adapted to support it to hold the pressure roll against the cylinder, a cross-piece connecting said journals, a frame in which said journals and cylinder are carried and including two ends, a rock shaft journaled in said ends, a rock arm on said shaft, a spring connecting said arm and said cross-piece, and a 115 device for limiting the turning of said rock shaft.

4. In a duplicating device, the combination with a cylinder and a pressure roll, of a swinging journal for each end of the roll, 125 a spring for each journal adapted to support it to hold the pressure roll against the cylinder, a cross-piece connecting said journals, a frame in which said journals and cylinder are carried and including two 130

ends, a spring connected to said cross-piece, a shaft extending between said ends, and a device connecting the spring to the shaft and adapted to vary its tension.

5. In a duplicating device, the combination with a cylinder and a pressure roll, of a swinging journal for each end of the roll, a frame comprising ends and supporting said cylinder and journals, a spring mounted upon the frame, for each journal to support it to hold the pressure roll against the cylinder, a cross-piece connecting said journals, a rock shaft beneath said cross-piece and journaled in the frame, a rock arm fast upon said shaft, a spring connecting said rock arm and said cross-piece, a device for varying the tension of the spring, and a finger-piece adapted to rotate the shaft to tension the connecting spring 20 to withdraw the roll from the cylinder.

6. In a duplicating device, the combination with a cylinder and a pressure roll, of a swinging journal for each end of the roll, a frame comprising ends and supporting said cylinder and journals, a spring, mounted upon the frame, for each journal to support it to hold the pressure roll against the cylinder, a cross-piece connecting said journals, a thumb screw threaded upon said 30 cross-piece and forming a shiftable anchorage, a rock shaft beneath said cross-piece and journaled in the frame, a rock arm fast upon said shaft, a spring connected to said anchorage and adjustably connected to said 35 rock arm, and a finger-piece adapted to rotate the shaft to tension the last-named spring to withdraw the roll from the cylinder and hold it withdrawn.

7. In a duplicating device, the combination with a frame and a cylinder journaled therein, of a roll, a swinging journal for each end of the roll, means for resiliently supporting said journals to hold the roll against the cylinder, a cross-piece connecting 45 the journals, a spring for drawing down on the cross-piece, means for adjusting the tension of the spring, and means for shifting the spring along the cross-piece.

8. In a duplicating device, the combination with a frame and a cylinder journaled therein, of a roll, a swinging journal for each end of the roll, means for resiliently supporting said journals, to hold the roll against the cylinder, a cross-piece connecting the journals, a spring for drawing down on the cross-piece, a rock shaft below the cross-piece, a rock arm fast upon the shaft, means for adjustably tensioning the spring to the rock arm, means shifting the 55 spring along the cross-piece, and means for rocking the shaft and holding it rocked to move the roll clear of the cylinder against the tension of the resilient support.

9. In a duplicating device, the combination with a frame and a cylinder journaled

therein, of a roll, a swinging journal for each end of the roll, means for resiliently supporting said journals to hold the roll against the cylinder, a cross-piece connecting the journals, a spring for drawing down 70 on the cross-piece, a rock shaft below the cross-piece, a rock arm fast upon the shaft, means for adjustably tensioning the spring to the rock arm, means for shifting the spring along the cross-piece, a second rock 75 arm fast to the shaft, a pivoted finger-piece, a link connecting said second arm and said finger-piece, and a stop for arresting said finger-piece when the link is carried past dead center to hold the roll in its clear position. 80

10. In a duplicating device, the combination with a frame and a cylinder journaled therein, of a roll, a swinging journal for each end of the roll, a spring for each journal, a set screw for adjusting the tension of each spring, to independently press each end of the roll against the cylinder, a cross-piece connecting said journals, and a third spring adjustable along the cross-piece to draw thereon against the tension of the first 90 springs to vary the pressure of the roll upon the cylinder.

11. In a duplicating device, the combination with a frame and a cylinder journaled therein, of a roll, a swinging journal for 95 each end of the roll, means for resiliently supporting said journals to hold the roll against the cylinder, a cross-piece connecting the journals, a spring for drawing down on the cross-piece, a squared thumb screw 100 adjustable upon the cross-piece forming an anchorage for the spring, an extension of said spring comprising a screw for adjusting it, a rock arm on which the screw draws, a rock shaft carrying said arm, and a finger-piece adapted to turn said shaft to carry the 105 roll clear of the cylinder.

12. In a duplicating device, the combination with a frame and a cylinder journaled therein, of a roll, a swinging journal for 110 each end of the roll, means for resiliently supporting said journals to hold the roll against the cylinder, a cross-piece connecting the journals, a spring for drawing down on the cross-piece, a squared thumb screw 115 adjustable upon the cross-piece forming an anchorage for the spring, an extension of said spring comprising a screw for adjusting it, a rock arm on which the screw draws, a rock shaft carrying said arm, a finger-piece journaled on the frame, a second rock 120 arm fast upon said shaft, a link connecting said second rock arm and said finger-piece, and stops limiting the throw of the shaft, one of said stops adapted to hold it when 125 the link is thrown past dead center.

BURNHAM C. STICKNEY.
